UNITED STATES PATENT OFFICE.

CORNELIUS J. BROSnan, OF SPRINGFIELD, MASS., ASSIGNOR OF TWO-THIRDS
TO H. A. GIBBS AND W. E. WRIGHT, BOTH OF SAME PLACE.

MACHINE FOR ATTACHING BUTTONS.

SPECIFICATION forming part of Letters Patent No. 335,211, dated February 2, 1886.

Application filed November 9, 1885. Serial No. 182,178. (No model.)

To all whom it may concern:

Be it known that I, CORNELIUS J. BROSnan, a citizen of the United States, residing at Springfield, in the county of Hampden and State of Massachusetts, have invented new and useful Improvements in Machines for Attaching Buttons, of which the following is a specification.

This invention relates to improvements in machines for attaching buttons, and is in the nature of an improvement upon my patent of October 6, 1885, No. 327,917, the object being to provide improved means for securing the positive movement of the button and the fastener or tack from their respective chutes into the troughs which lead to the place on the machine where they are fastened to the material, and to provide improved tack-clamping mechanism under the anvil.

A further object of this invention is to provide, in combination with the machine embracing said improvements, improved button and tack feeding devices, and improved means for holding the button while it is being fastened onto the material.

In the drawings, forming part of this specification, Figure 1 is a perspective view of the machine, the lower part of the frame and the lower end of the pedal-connecting rod being broken away. Fig. 2 is a front elevation of that part of the frame supporting the anvil and tack-clamps, and of the front end of the button-trough, showing a button in position to have the fastening-tack pass through its eye, said tack and the clamp-springs being shown in dotted lines. Fig. 3 is a side elevation of the parts referred to in the description of Fig. 2, showing the front parts of the frame and the button and tack troughs, the upper end of one of the clamps being broken away and the clamp-block being shown partly in section, in order to show the tack plunger or lifter and the tack in full lines, the latter being in the position when it is about to enter the eye of the button. In this figure (3) are shown in dotted lines the lower end of the button-plunger and the end of its operating-arm. Fig. 4 is a side view of the front end of the button-trough; and Fig. 5 is a cross-section of the same on line $\alpha\alpha$, showing the laterally-

moving button-holder and the end of its spring in full lines. Fig. 6 is an enlarged view of said button-holder in perspective. Fig. 7 is an elevation of a part of that portion of the machine at the lower end of the button-chute, Fig. 1, showing the lower end of the latter in dotted lines, a part of the button-plunger and the button-trough, and the devices by which the button is transferred from the chute to the latter. Fig. 8 is a view taken transversely on line $\alpha\alpha$, Fig. 7. Fig. 9 is an elevation of the rear side of the button-carrying wheel. Fig. 10 is a plan view under the button-trough, showing a part of the frame in section and the carriage to which the button and tack plungers are attached, the connection of said carriage with the rock-shaft, a portion of the arm on the latter to which the foot-pedal is connected, and of the button-plunger shank, the tack-trough, the lower end of the tack-chute, and the mechanism which controls the movement of the tacks from the chute into the tack-trough. Fig. 11 is a similar view to Fig. 10, but showing said tack-controlling mechanism in a different operative position to that shown in Fig. 10.

The mechanism shown and described in my said patent for moving the buttons and fasteners to the front end of the machine under the anvil, where they are united on the material, for operating the vertically-moving tack-carrier and the anvil itself, are substantially the same as those parts of the machine which are the subject of this application.

The construction and operation of the tack-reservoir and feeding mechanism J is that shown and described in my patent dated October 27, 1885, No. 329,268, to which reference may be had.

The improvements embodied in the button-reservoir and feeding mechanism H form no part of the subject-matter of this application, but the construction and operation of said button-feeding mechanism are clearly set forth in another application for a patent, which is filed by myself simultaneously with this, dated November 13, 1885, Serial No. 182,700.

In the drawings, A is the frame of the machine, (the lower part thereof being broken away,) which is in practice adapted to be at-

tached to a suitable table, under which is hung a treadle, and to the latter the connecting-rod F is attached, its upper end being pivotally connected to the arm E on shaft C. A suitable retracting-spring is attached to said connecting-rod to draw it downward, and by means of said treadle and spring a rocking motion is given to said shaft, which runs transversely across the frame A, the part of the latter in which said shaft has its bearings being hollow and open at the rear side, to permit of the requisite vibratory motion of arm E.

The button-trough i and the tack-trough h are arranged parallel to each other, and have operating in them plungers which are given a reciprocating motion, as in said patent, to carry a button and a tack simultaneously under the anvil 8, said reciprocating motion of the plungers being imparted thereto by the yoke or carriage d, (see Figs. 1 and 10,) the latter being connected by a short connecting-rod, 22, with an arm, 21, attached to the rock-shaft C. The lower end of said carriage enters the tack-trough h, and said tack-plunger is attached to said end, substantially as shown in said patent. The button-plunger proper, g, is attached to the carriage d by the shank g. The anvil 8 is fixed in the front end of the frame A, and is constructed substantially as in said patent. The button-trough i extends to the front of the anvil, and lies close by the side of the latter, as shown in Figs. 1 and 3, and opposite the anvil in said trough is located the laterally-moving button-holder 15, (see Fig. 6,) its body of cylindrical form, having a square head, (or substantially so,) 20, and a wing, 19. Said button-holder is inserted in the button-trough i in the position shown in Figs. 2, 4, and 5, and is held normally in that shown in Fig. 2 by a flat spring, 16, having a bifurcated end engaging with the head 20 of the holder, said spring being secured on the outside of the said trough by a screw, as shown in Fig. 4 in dotted lines. The holder has a lateral movement toward and from the side of the anvil 8, the spring giving it the former action, and when a button is carried through trough i to the side of the anvil it encounters the curved end 18 of the holder, forcing the latter back against the spring, and when the button-plunger retires the latter forces the holder against the button and the latter against the side of the anvil, holding it in the position shown in Fig. 3, with its eye in a position to let the fastener 24 pass through it, and the latter being by the carrier 17 forced against the anvil is made to pass through the material to which the button is to be attached and to be hooked around the button-eye, as set forth in said patent. The next button that is carried to the anvil drives the one before attached out of the machine, or from between the said holder and the anvil.

65 The rear side of the clamp-block 9 is cut away, as shown in Fig. 3, opposite the end of

the tack-trough h, to allow the fastener 24 to pass from the trough into the block to the position shown in Fig. 2, when the carrier 17 is down, the upward movement of the latter carrying the fastener to the position shown in Fig. 3; and from that to the one above described, which completes the fastening.

The tack-clamps 10 are pivoted in grooves on each side of the clamp-block 9, as shown, and between the inner side of each clamp and the adjoining side of the groove in which it is pivoted is secured a flat spring, (shown in dotted lines in Fig. 2,) whose upper end engages in a notch in the clamp. Said springs hold the upper ends of the clamps 10 together, and when the tack 24 is forced up between them the latter is caused to enter between two opposite notches in the clamps, and thereby and by the action of said springs is made to take a proper position, and is so held as not to be easily moved from said position.

The chute e' from the tack-feeding devices J is connected to the side of the tack-trough h, as shown in Figs. 10 and 11, and the tacks move by gravity down the inclined chute to the side of the trough; but to prevent more than one tack at a time from entering or partly entering said trough, and to hold back the tacks which are behind the lower one and to positively place the latter one in said trough, the following described mechanism is applied to this machine.

A slide, n, having oblong screw-holes through it, as shown, is, by screws on which it slides, attached to the side of the tack-trough h. A vibratory tack separator and mover, o, is pivoted on the slide n, and has a vibrating motion in the plane of the tack-trough. One end of the separator is of wedge shape, and on one side, near its opposite end, is a laterally-extending short arm, against the end of which the spring m bears, the latter being attached to slide n, and on the opposite side of the separator is a laterally-extending hook, as shown. A rod, i', is connected with the rear end of the slide n, and extends rearwardly, passing through the arm s on the carriage d, as shown in Fig. 10. Rod i' is provided with two nuts or abutment-blocks, x x, between which the arm s has a reciprocating motion, whereby the slide n and the separator thereon are moved toward and from the side of the tack-trough e', their movement toward the latter being adjusted by the nut or nuts on rod i'. A pin, 23, is placed in the upper side of trough h, which stands up in the track of the said hook on the separator o.

The operation of the separator is as follows: When the carriage d moves toward the clamps 10, the tack 24, Fig. 11, is pushed along in front of the end of the above-described plunger in the trough h onto the carrier 17, and by said movement of the carriage the slide n and the separator are moved about to the position shown in Fig. 10, letting the tacks take substantially the positions there shown. The re-

- verse rearward movement of carriage *d* causes slide *n* to move toward the chute *c'* and the pointed end of the separator to be introduced between the two tacks nearest said trough. 5 The hook on the separator then engages with pin 23, causing said separator to vibrate and carry its free end against the tack nearest the trough *h*, moving it into the latter, as shown in Fig. 11, and holding back the other tacks. 10 When the slide *n* and the separator move from the chute *c'* to reassume the positions shown in Fig. 10, the spring *m*, acting on the aforesaid short arm on the side of the separator, swings the latter to said position, the pin 23 15 by said movement of the slide *n* being disengaged from said hook.

In my said patent the buttons move from the chute by gravitation, entering the button-trough one by one through an opening in the 20 side of the latter, said chute being connected directly to said trough. In practice it is found that the movement of the buttons by gravitation from the chute into the trough is not sufficiently positive to insure such a constant supply of buttons at the anvil as is desirable, especially when the buttons must move in a curved chute in order to bring them into proper position when they enter the button-trough, whereby the eye of the button, when 25 the latter arrives at the anvil, is extended under the latter, as in Fig. 3, and to render the movement of the buttons positive from the chute *c'*, which conducts the buttons from the reservoir *H* into the trough *i*, the below-described mechanism receives the buttons one by one from said chute and deposits them in trough *i* in said requisite position. 30

A wheel-support, *D*, (shown in Fig. 1 and in enlarged views in Figs. 7 and 8,) is attached 40 to the upper side of frame *A* at the lower end of the chute *c'*, and nearly opposite the said opening in the side of the trough *i*, through which the latter is supplied with buttons, the upper part of said support extending over the 45 tack-trough and nearly to the trough *i*. A wheel, *y*, (shown, respectively, in edge and front elevation in Figs. 7 and 8,) is pivoted on the side of support *D* opposite the end of the button-chute *c'*, the position of the end of the 50 latter relative to the wheel being shown in dotted lines in said Fig. 7, the end of said chute being attached to the center pivot, 28, of the said wheel, or in such a position as to bring the channel in the chute to correspond 55 with the slots 3 in the periphery of the wheel. The rear side of wheel *y* has a series of wide ratchet-teeth, (one to each space between slots 3,) 6, on its rear side, as shown in Figs. 7 and 9, and between said slots pins 2 are inserted in the periphery of the wheel. The 60 slots 3 serve to receive the eye of the button, as shown. The wheel rotates in the direction of the arrow on Fig. 8.

A pawl-carrier, *f*, having oblong screw holes 65 or slots through it, is secured on the upper end of the support *D* by screws passing through

said slots to allow said carrier to have a reciprocating sliding motion on the support. The rear end of carrier *f* is inclined to its direction of motion, as shown, and a spring, 7, secured between it and frame *A*, serves to move it toward the latter. Two posts, 5, one behind the other in Fig. 8, depend from the under side of carrier *f*, and in the one nearest the vertical side of the support *D* is pivoted 70 the pawl 4, against the rear end of which the free end of the spring *v* (which is attached to the end of the carrier) bears, serving to swing the pawl to the position shown in Fig. 8, the end of the latter lifting slightly as the pawl 75 retires after having moved against one of teeth 6 to rotate wheel *y*. A stop-arm, *w*, is pivoted to the lower part of support *D*, and has a vibratory motion caused by the movement of one of pins 2 on wheel *y* against its inclined 80 edge near its free end, and the spring *z*, which bears against its opposite edge. When said wheel is rotated, as hereinabove described, and is brought to a proper position to deliver a button into trough *i*, the upper end of arm *w* 85 swings under one of pins 2, as shown, and the outer one of said posts 5 is brought by the forward movement of the carrier *f* over said pin, thereby preventing said wheel from having inadvertently any movement at the instant 90 that it discharges its button into the trough, whereby the button might fail of proper placement. 95

A carrier-actuating bar, *e'*, having a beveled end, as shown in Figs. 1 and 7, is attached by 100 one end to the carriage *d*, and by the latter is given a reciprocating motion in a direction at right angles to the carrier *f* and opposite its inclined end. A guide-spring, 14, extends from the upper side of trough *i* (see Fig. 8) 105 over the wheel *y*, against which the button is carried when moving toward the trough *i*, and whereby it is held steadily in engagement with the wheel until it is deposited in the said trough. A steady-pin, 13, is placed in support *D*, over wheel *y*, beneath which the button is delivered from chute *c'*, and whereby it is prevented from being displaced by the crowding against it of the buttons back of it. 110

The tack-reservoir *J* and button-reservoir *H* are both secured on the shaft *K*, which has an intermittent rotary motion in suitable bearings in the arms *B*, which are secured to frame *A*, said motion being given to the reservoirs by means of ratchet mechanism connected 115 with said shaft and the arm *a*, (as described in my said patent,) the latter being connected to arm *b* on the rock-shaft *C* by the connecting-rod *a'*. Said reservoirs operate to separate and deliver therefrom, one by one, 120 tacks and buttons into the chutes *c* and *c'*, which are placed in each of said reservoirs in a mass, the operation of each being fully set forth in the above-named patent of October 27, 1885, and in my said application for a patent. 125 The tacks from the reservoir *J* follow the chute *c'* directly to the side of trough *h*, 130

and are admitted to the latter, as above described. The buttons in like manner follow the chute *c*, and from the lower end of the latter are lodged, one by one, by gravitation 5 on the wheel *y* in the position shown in Fig. 8. The operator stands in front of the machine, holding the material, leather, or cloth, upon which the button is to be fastened, between the anvil and the clamps 10. When the operative parts are at rest, or before the said foot-treadle is operated, the button and tack plungers are in a rearward position, leaving the troughs free to receive a button and a tack in front of the ends of said plungers, and when 10 the latter are in said position the end of the bar *e* is retired rearwardly, thus having permitted spring 7 to slide the carrier *f* toward trough *i*, and causing pawl 4 to engage with and rotate wheel *y*, and carry the button thereon over and drop it into said trough. The operation of the foot-treadle then causes said plungers and the said bar *e* to move forward, the latter striking the inclined end of carrier *f* and sliding it to the position shown 15 in Fig. 8, and the plungers moving said button and tack forward under the anvil, as above described, where they are attached to the fabric by the action of the tack-carrier 17, as above described, after which the parts retire to repeat the operations. The wheel *y* is prevented from rotating by the backward motion of the pawl 4, as its end drags over the edge of the teeth 6, by the pivoted arm *w*, which during said motion of the pawl occupies the position under pin 2 of the wheel. (Shown in 20 Fig. 7.)

What I claim as my invention is—

1. In a machine for attaching buttons, the combination, with the button-reservoir *H* and the button-chute *c* leading therefrom, of the wheel *y*, located at the end of said chute and having radial slots in its periphery to engage with the shanks of the buttons as they escape from said chute, the button-trough *i*, to 25 receive the buttons from said wheel, and a

reciprocating pawl-carrier having a pawl thereon engaging with said wheel, whereby the latter is intermittently rotated, substantially as set forth.

2. The button-carrying wheel *y*', provided 50 with ratchet-teeth, substantially as described, and having the pins 2 in its periphery, the pawl-carrier *f*, having the pawl 4 pivoted thereto, the bar *e*', having a reciprocating movement at the end of said carrier, the spring 55 7, and the pivoted stop-arm *w*, combined and operating substantially as set forth.

3. In combination, the button-reservoir *H*, the chute *c*, to convey buttons from the latter, the wheel *y*, located at the end of said chute, and having radial slots in its periphery to engage with the shanks of the buttons as they escape from said chute, the button-trough *i*, to receive buttons from said wheel, the button-plunger *g*', having a reciprocating motion 60 in said trough *i*, and the reciprocating pawl-carrier *f*, having a pawl thereon engaging with said wheel, substantially as set forth.

4. The tack-trough *h*, the chute *c*', connected to the side of the latter, the separator *o*, having on its opposite edges, substantially as described, a short arm and a hook, and pivoted to the slide *n*, the spring *m*, bearing on said arm, the pin 23, fixed in the side of the trough *h* in the path of the movement of said hook, 70 and means, substantially as described, for imparting a horizontal reciprocating movement to said slide, combined and operating substantially as set forth.

5. The button-trough *i*, the laterally-moving 80 button-holder 15, passing through said trough opposite the side of the anvil, the spring 16, to press the holder toward the latter, and the anvil 8, combined and operating substantially as set forth.

CORNELIUS J. BROSNAH.
